(57) **CLAIM**

The ornamental design for a side burner, as shown and described.

DESCRIPTION

FIG. 1 is a top front isometric view of a side burner showing the design.

FIG. 2 is a bottom rear isometric view of the side burner of FIG. 1.

FIG. 3 is a front elevation view of the side burner of FIG. 1.

FIG. 4 is a rear elevation view of the side burner of FIG. 1.

FIG. 5 is a left elevation view of the side burner of FIG. 1.

FIG. 6 is a right elevation view of the side burner of FIG. 1.

FIG. 7 is a top plan view of the side burner of FIG. 1.

FIG. 8 is a bottom plan view of the side burner of FIG. 1.

FIG. 9 is a top front isometric exploded view of the side burner of FIG. 1 showing the griddle plate element separated from the side burner.

FIG. 10 is a top rear isometric view of the side burner of FIG. 1 in a second configuration in which the griddle plate element is removed.

FIG. 11 is a front elevation view of the side burner of FIG. 10.

FIG. 12 is a rear elevation view of the side burner of FIG. 10.

FIG. 13 is a left elevation view of the side burner of FIG. 10.

FIG. 14 is a right elevation view of the side burner of FIG. 10.

FIG. 15 is a top plan view of the side burner of FIG. 10; and, FIG. 16 is a bottom plan view of the side burner of FIG. 10. The dashed lines in the drawings illustrate portions of the side burner that form no part of the claimed design. The shading lines shown in the drawings represent the three-dimensional contour of the claimed design and are not intended to indicate surface decoration.
